Int. Cl. D26—02; D29—02
U.S. Cl. D48—24 R

FIG. 1

FIG. 2

FIG. 3

FIG. 4

FIG. 5

FIG. 1 is a perspective view of an emergency warning light embodying my new design;

FIG. 2 is a front elevational view;

FIG. 3 is a top plan view;

FIG. 4 is an enlarged fragmentary view of the upper portion of the emergency warning light; and

FIG. 5 is a front elevational view of a second embodiment of my new design.

The characteristic features of my design reside in the panels which appear through the lens, said panels being shaded to indicate contrast.

I claim:

The ornamental design for an emergency warning light, as shown and described.
